TYPEWRITING MACHINE

Charles Walker, Syracuse, N. Y., and Willard H. Wade, Washington, D. C., assignors to L. C. Smith & Corona Typewriters, Inc., Syracuse, N. Y., a corporation of New York

Application February 9, 1943, Serial No. 475,264

15 Claims. (Cl. 197—74)

The invention relates to improvements in typewriting machines, and its general purposes are to provide improved power means for effecting actuation of a reciprocal operation-effecting element of such machines, and to provide improved key-controlled means whereby movements of an element of such machines from and back to a normal idle position may be effected by force other than that exerted by the typist on one or more control keys of said means.

While the invention is particularly adapted for embodiment in case changing mechanisms for typewriting machines, and a preferred embodiment of the invention wherein case changing movements of a type bar segment of a typewriting machine are effected at will is illustrated in the accompanying drawings forming a part of this specification, it will be obvious to those skilled in the art that the invention, in its broader aspects, may be employed for effecting movement of other elements of a typewriting machine from and to a normal idle position by power other than that exerted on a control device, whether said element be movable for case changing or for other purposes.

Particular objects of the invention are to provide an improved case changing mechanism for typewriting machines, and to provide a case changing mechanism wherein movement of the case-changing shiftable support (such as a type bar segment) to a normal position for lower case typing is effected by spring power, and movement of said support to a position for upper case typing is effected by gravitational force, power derived from a rotary motor or shaft being utilized to free the case-changing support from the influence of the spring power and also, preferably, to release a locking device normally locking the support in its normal position for lower case typing.

A further object of the invention is to provide improved means for controlling a power case-changing mechanism by means of two "temporary shift" keys and a "shift-lock" key.

Other objects and advantages of the invention will appear from the following description of the illustrative embodiment thereof shown in the accompanying drawings.

In the drawings,

Figure 1 is a top plan view of a typewriting machine equipped with a case shift mechanism embodying the invention, certain parts of the machine being omitted and others broken away for greater clarity of illustration of the case shift mechanism.

Figure 2 is a fragmentary vertical longitudinal sectional view of the machine taken approximately on the line 2—2 of Figure 1, the parts being positioned for normal lower case typing.

Figure 3 is a view similar to Figure 2 showing the machine conditioned for upper case typing with the left hand one of the two "temporary shift" keys of the machine held depressed.

Figure 4 is a fragmentary sectional view similar to Figure 3 but showing the "shift lock" key latched in depressed position.

Figure 5 is a detail view partly in horizontal section approximately on line 5—5 of Figure 2.

Figure 6 is a fragmentary sectional view taken on the same line as Figures 2 and 3, but showing the parts as in action during downward shifting of the type bar segment from its normal position for lower case typing to its shifted position for upper case typing.

The drawings illustrate the invention as embodied in a case shift mechanism for a typewriting machine, such as the known L C Smith typewriter, having a platen carriage and an upwardly and rearwardly inclined type bar segment, which segment is constructed and is shiftably mounted in the framework of the machine, substantially as shown, for example, in United States patents to Gabrielson numbered 983,490, 1,018,968, 1,032,131 and 2,028,200, for downward movement of the segment relatively to the carriage from a normal position conditioning the machine for lower case typing into a lower shifted position conditioning the machine for upper case typing.

The machine has a suitable stationary main framework 10 upon which the usual platen carriage 11 is mounted in the usual manner for travel back and forth transversely of the machine, and the usual roller platen 12 is journaled in said carriage. The usual type bar segment 13 supports the usual arcuate set or system of upwardly and rearwardly swingable type bars 14, each type bar having a pivotal connection 15 with the segment and also bearing a lower case type 16 and an upper case type 17, only a few of said type bars being shown.

The type bar segment 13 is supported and guided in the main framework 10 by means constructed and arranged substantially as disclosed in the aforesaid patents, for down and up case-changing movement of the segment respectively from and to its normal position for lower case typing. Said supporting and guiding means comprises two raceway members 18 fixedly held to opposite ends of the segment 13, two raceway members 19 fixed on the framework 10 adjacent

opposite sides of the machine and opposed to members 18 to provide two upwardly and rearwardly inclined ball races, two bearing balls 48, one in each of said races, a horizontal rock shaft 20 extending transversely of the machine and journaled at its ends on pivots 49 held to framework 10, and a pair of normally forwardly and upwardly extending rock arms 21 (Figure 1) fixed on shaft 20 and pivotally connected at their forward ends to segment 13 by horizontal pivots 22 extending transversely of the machine.

The normal elevated position of the segment for lower case typing and the shifted or lowered position of the segment for upper case typing are determined by case shift stop means adjustable to vary each of said positions independently of the other and constructed substantially as shown in Patent No. 2,028,200 previously referred to. This adjustable stop means, as shown, comprises a stop screw 88 pendent from the segment 13 and variably screwable thereto to adjust the head of the screw relatively to the segment. The shank of this screw extends loosely through an aperture 89 in a fixed stop part 10a of the framework 10 against the under face of which part 10a the head of said screw is engageable to determine the position of the segment for lower case typing. Above part 10a a stop, comprising a nut 90, is screwable up and down on the shank of screw 88 for adjustment relatively to the segment and is engageable with the upper face of stop part 10a to determine the position of the segment for upper case typing.

The improved means shown in the drawings whereby case changing movements of the segment may be effected at the will of the typist will now be described.

The shaft 20 has fixed thereto adjacent the left hand side of the machine a rock arm 23 which normally extends upward and forward from said shaft. A plate 24, adjustable about shaft 20 and located at the left hand side of rock arm 23, is clamped in adjusted position to said arm, to rock therewith, by means of a clamping screw 25 which is threaded into said arm with its shank extending through a clearance slot 24b in the plate, said plate being pivoted on shaft 20 by a forked portion 24a of the plate, the tines of which forked portion are engaged in an annular groove in the shaft. Plate 24 extends above arm 23 and has fixed to its upper portion a horizontal stud 26 which projects from the plate toward the adjacent left hand side of the machine.

Preferably there is provided a normally straightened locking toggle for normally releasably latching or locking the segment in its normal elevated position conditioning the machine for lower case typing. This toggle comprises a front link 27 and a rear link 28 which are hinged together by a horizontal hinge pivot 29 extending transversely of the machine. The front link 27 is pivotally anchored on a fixed toggle anchor pivot element 30 which is fixed on framework 10 and extends horizontally transversely of the machine, and the rear link 28 is pivotally anchored to the above described stud 26, which stud serves as the movable anchorage of the toggle and is also adjustable, as above explained, by adjustment of plate 24. The front link 27 of said toggle is formed adjacent its rear end with a rearwardly extending stop finger 32 which is permanently adjustably bendable up and down for engagement of said finger over a stop 33 fixed on the rear link 28 between the toggle hinge 29 and toggle anchor 26 to permit upward breaking or

collapsing of the toggle but prevent downward breaking of the toggle from its normal fully straightened or extended condition. Preferably, a light pull spring 31 is connected at its forward end to framework 10 and at its rear end to toggle link 27 forward of the toggle anchor 30 to aid in full straightening of the toggle 27-28 and to yieldingly resist upward breaking or collapsing of the toggle. When the toggle 27-28 is broken or collapsed slightly by a camming action on the toggle hinge pivot 29 of a cam edge 34 on a link 35, upon initial forward movement of link 35, as hereinafter described, the segment 13 is freed or released from the locking restraint of said toggle.

The improved means shown in the drawings whereby downward shifting of the segment by the force of gravity into its lower position for conditioning the machine for upper case typing and whereby restoration of the shifted segment to normal position by spring force, are brought about at the will of the operator, will now be described.

Movement of the segment 13 downward by gravitational force into its position for conditioning the machine for upper case typing is brought about by motor driven forward movement of a reciprocal case-change-effecting link or bar 35 from a normal spring-returned position of said bar, and rearward movement of said link or bar to the normal position thereof by a power spring 43 brings about restoration of the segment to its normal elevated position for conditioning the machine for lower case typing.

The link or bar extends fore and aft of the machine adjacent the left hand side of the machine and is supported for reciprocation thereof substantially endwise. The link is made in two sections connected for relative longitudinal adjustment therebetween to vary the length of the link, said link sections being clamped together in adjusted relation by means of clamping screws 91 threaded in one section and extending through longitudinal slots 92 in the other section. Adjacent its forward end the link 35 is slidably supported and guided by the toggle anchor stud 26 carried by plate 24, said stud extending through a longitudinal guide slot 36 in the link 35. The hinge pivot 29 of toggle 27-28 projects toward the right hand side of the machine and is normally located over, and preferably slightly spaced above, the forward portion of a downwardly and forwardly inclined cam edge 34 formed on link 35 at the upper edge of the link adjacent the forward end of the link. A slight initial forward movement of link 35 will cause cam edge 34 to move the toggle hinge pivot 29 upward slightly to initially break the toggle and release the segment. As the released segment drops, the toggle will continue to collapse.

At its rear end the link 35 is connected to the upper end of the upstanding arm 38 of a three-arm lever 38-40-41 by a horizontal pivot 37 which extends transversely of the machine. Said lever is formed with a hub 39 from which its arms extend, the arm 40 extending forwardly and the arm 41 extending rearwardly from the hub 39. Hub 39 is journaled on a cylindrical sleeve 131 which extends horizontally transversely of the machine adjacent the left hand side of the machine and the rear end of the machine. The left hand end of this sleeve extends through a part of framework 10 and is stationarily held to said frame part.

A power shaft 42, which extends horizontally transversely of the machine adjacent the rear

end of the machine, is journaled in sleeve 131 and is also journaled in framework 10 at 132. While the machine is in use, this power shaft 42 is constantly rotatively driven clockwise (as viewed in Figures 2, 3 and 6) by a rotary electric motor 62 which is suitably mounted on framework 10 and drives said shaft through suitable speed-reducing driving means 63, the motor being constantly energized while the machine is in use.

Power for restoring the segment 13, the parts supported thereby, and the link 35 and lever 38-39-40-41 to their respective normal positions and yieldingly holding them there is afforded by a constantly tensioned power spring, namely, the pull spring 43. This spring is anchored at its forward end to the rear section of link 35 and is anchored at its rear end to the forward end of a bolt 45. This bolt is longitudinally slidabile fore and aft of the machine through a guide aperture in a part of framework 10, and there is threaded on this bolt a nut 46 which abuts the rear face of said apertured part of the framework. By screwing this nut along the bolt the normal tension of spring 43 may be varied. Concomitant return movements of the link 35, and of the three-arm lever 38-39-40-41 connected therewith, are arrested by engagement of a pin 65 on the rearwardly extending arm 41 of the lever with the upper side of an up and down adjustable stop lug 93 formed on a part of the framework 10. Pin 65 extends horizontally transversely of the machine, and the stop lug 93 is permanently adjustably bendable up and down for regulation of the normal position of the link 35 and of the three-arm lever.

Means, hereinafter described, are provided for moving both the three-arm lever and the link or bar 35 a predetermined extent from their respective normal positions in opposition to the power of spring 43 by power derived from the above-mentioned constantly rotating shaft 42, the extent of the forward movement of the link being preferably greater, as shown in Figure 3, than that necessary to permit the segment 13 to drop under the influence of gravity until arrested by engagement of stop 90 with the frame stop part 10a. In the normal position of link 35, the forward end wall of slot 36 engages the stud 26, but in the fall forwardly shifted position of link 35, the forward end wall of slot 36 is preferably spaced forwardly more or less from stud 26 as shown in Figure 3. In returning to normal position under pull of spring 43, the link 35 pulls on stud 26 until the upward movement of the segment 13 is arrested by engagement of the head of stop screw 88 with stop frame part 10a, which engagement occurs at the limit of return or rearward movement of link 35 determined by engagement of pin 65 with the adjustable frame stop 93. Stud 26 and slot 36 provide a one-way power transmitting connection between the link 35 and the segment for lifting the segment.

A second, and normally broken or collapsed, toggle is provided for releasably latching or locking the link 35 and the three-arm lever 38-39-40-41 against return movement by the power spring 43 from the aforesaid predetermined limit of shifted movement thereof out of normal position. This toggle becomes fully straightened into locking condition as the link and three-arm lever arrive at their predetermined shifted limits from normal position. The toggle comprises an

upper link 51 pivoted on an anchor pivot screw 52, and a lower link 53 hinged to the upper link by a hinge pivot 54 and pivotally anchored to an anchor pivot 55 fixed on the forward end of arm 40 of the three-arm lever. The axes of pivots 52, 54 and 55 extend horizontally transversely of the machine. Anchor pivot 52 is fixed to a vertically adjustable plate 94 provided with aligned vertically extending slots 95 through which extend clamping screws 96 threaded into a fixed part of framework 10 to clamp plate 94 to the framework with the toggle anchor pivot 52 in desired vertically adjusted position for full straightening of the toggle at the predetermined shifted limit of movement of link 35 and the three-arm lever. A light pull spring 56, anchored at its upper end to plate 94 and anchored at its lower end to toggle link 51 forward of anchor 52, is preferably provided to aid in fully straightening toggle 51-53 and to yieldingly resist breaking of the toggle. This toggle is normally collapsed or broken rearwardly, and the link 51 of the toggle is provided with a stop finger 57 which is permanently adjustably bendable toward and from a stop 58 fixed on toggle link 53, which finger 57 engages said stop 58 when the toggle is fully straightened and prevents forward collapsing of the toggle.

Means, which will now be described, are provided for imparting, at the will of the typist, the aforesaid predetermined throw to the three-armed lever 38-40-41 and the connected link or bar 35 from normal position to shifted position by power derived from shaft 42 for effecting conditioning of the machine for upper case typing, and for thereafter effecting, at the will of the typist, release of said connecting link and lever from the locking action of the toggle 51-53 to permit restoration of said link and lever and the segment 13 to normal position by the power spring 43 for conditioning the machine for lower case typing.

Shaft 42 is connectible by the following power-driven means with the three-arm lever, to first impart the aforesaid predetermined movement to said lever and the connected link 35 and permit automatic locking of the lever and link in shifted position by toggle 51-53, and to thereupon leave said lever and link free to be restored to normal position by power spring 43 when said link and lever are released from the locking action thereon of the toggle 51-53.

The just-mentioned power-driven means comprises a mutilated pinion 66, a single-revolution clutch for connecting said pinion to shaft 42 for a single driven revolution of the pinion, and a vibrative or reciprocal rack 47 which is connected to the three-arm lever, these parts being arranged to effect, during each revolution of the pinion, automatic engagement of the pinion with said rack to drive the rack in one direction to impart the previously described predetermined throw from normal position to the lever, automatic disengagement of said pinion from the rack, and arrest of the pinion in a normal position in which no teeth of the pinion are in the path of movement of the teeth of the rack. Preferably, means are provided for positively releasably locking the pinion in its normal arrested position.

In the construction shown, the vibrative or reciprocal rack 47 is a segment rack journaled on a horizontal pivot 64 which is fixedly held to framework 10 behind shaft 42 and extends parallel to said shaft, said rack being formed with an oper-

ating arm behind its pivotal axis provided with a slot 41a (Figures 5 and 6) which is radial to the pivot 64 and in which is engaged the previously described horizontal pin or stud 65 fixed on, and extending transversely of the machine from, the arm 41 of the three-arm lever. The rack is thus also movable by spring 43 to a normal position determined by engagement of stud 65 with stop 93, and driving of the rack by multilated pinion 66 from said normal position imparts the previously mentioned predetermined throw from normal position of the three-arm lever and the link 35.

The mutilated gear or pinion 66 is loosely journaled on shaft 42 in front of the segment rack 47 and has fixed on its hub a short arm 97 to which a dog-carrying plate 67 is positively held by suitable means to rotate with the pinion 66. In the construction shown, the dog-carrier or plate 67 is loosely journaled on a suitable spacing collar on the pinion hub and is positively held to arm 97 by a rivet 98, so that the dog carrier rotates in unison with the multilated pinion.

The single-revolution clutch above referred to includes a driving clutch element or ratchet wheel 68 which is fixed on shaft 42, and a driven clutch element or clutch dog 69 which is pivoted on the dog-carrier 67 at 70 for swinging of said dog into and out of engagement with said ratchet wheel. A torsion spring 71 (Figure 6) is engaged with the dog and dog-carrier to urge the dog into engagement with the toothed periphery of the ratchet wheel for driving of the multilated pinion by the ratchet in clockwise direction as the parts are viewed in Figures 2, 3 and 6. The clutch is thus constantly biased to close for driving the mutilated pinion.

The normal position of the segment rack 47 is determined, as above explained, by engagement of pin 65 with the adjustable stop 93. The normal arrested position of the mutilated pinion 66 and the dog-carrier is determined by releasable latch means a part of which also controls throwing of the clutch dog into and out of engagement with the ratchet wheel and normally hold the clutch dog from engagement with the ratchet wheel. This latch means comprises a latch lever 72-73-74 fulcrumed on a horizontal pivot 75 on framework 10, which pivot extends transversely of the machine below shaft 42 and pinion 66 and the dog-carrier. The lever 72-73-74 is formed with a stop finger 76 which is permanently adjustably bendable fore and aft of the machine and is normally urged forward against a stop portion 77 of framework 10 by a return spring 78 to determine the normal position of said lever and thereby determine also the normal position of the multilated pinion 66 and dog-carrier 67. Spring 78 is anchored to arm 73 of said lever and to a control bar or tappet 110 hereinafter described. Arm 72 of said lever is formed with a laterally bent stop lug 79 which normally is interposed in the path of driven movement of the dog-carrier 67 and is normally engaged by said carrier. The clutch dog 69 has a tail piece 69a which, following a clutching engagement of the dog with the ratchet wheel 68, is adapted to engage against lug 79 slightly before the dog-carrier engages said lug and to bring about a rocking of the dog on its pivot 70 to move the nose of the dog out of engagement with the teeth of the ratchet wheel at the end of a single revolution of the multilated pinion and thereafter hold the clutch elements 68-69 disengaged until lever 72-73-74 is again rocked to again release the

dog carrier and dog. Lever 72-73-74 thus also serves as a clutch control lever for the clutch 68-69.

To prevent the dog spring 71 from reversely rotating the dog-carrier and pinion, after arrest of the dog-carrier and disengagement of the dog from the ratchet wheel, and to prevent possible accidental reverse rotation of the dog-carrier and pinion from normal position, there is loosely pivoted on the previously mentioned pivot 75 a latch arm 80 which is normally urged by a spring 81 against a stop lug 82 on arm 72 of the lever 72-73-74 into a position for closely confining a part of the dog-carrier between the free end of said latch arm 80 and the lug 79 on the lever 72-73-74. Spring 81 is anchored to latch arm 80 and to arm 72 of the lever 72-73-74 and, as the dog-carrier nears the end of each revolution thereof, said dog-carrier engages and rocks arm 80 out of the way of the dog-carrier until the free end of the arm 80 snaps behind the part of the dog-carrier which abuts lug 79. Arm 80 does not engage the tail 69a of the clutch dog 69.

It will be observed that the motor, clutch and multilated pinion are normally ineffective to drive the rack 47 notwithstanding the fact that the motor is constantly running while the machine is in use.

The following case-selecting means are provided for controlling, at the will of the typist, the shifting from normal position and the restoration to normal position of bar 35, lever 38-40-41 and rack 47 by the above described electric motor actuated mechanism and the power spring 43 and thereby, in the construction shown, effecting a gravity shift of the type bar segment 13 into its position conditioning the machine for upper case typing and spring restoration of the segment to its normal position conditioning the machine for lower case typing.

A straight fulcrum rod 100, which extends horizontally transversely of the machine, is fixed on framework 10 below the forward ends of the type bars 14 of the system of type bars with said rod crossing a series of slots 101 formed in a part of the framework. This fulcrum rod preferably is the fulcrum rod for the type key levers of key-controlled power-actuated type bar actions for the type bars 14, which actions are preferably constructed and operate as disclosed in the co-pending application for United States patent of Charles Walker, Serial No. 466,989, filed November 26, 1942.

A spring-retumed tappet-actuating lever 102-102a is fulcrumed on rod 100 adjacent the left hand side of the machine. Also fulcrumed on said rod adjacent opposite sides of the machine are two "temporary shift" key levers 103, the left hand one of which is located close to, and at the right hand side of, the tappet-actuating lever 102-102a. Also fulcrumed on said rod close to, and at the left hand side of the tappet-actuating lever, is a "shift lock" key lever 104. Each of said three key levers and said tappet-actuating lever is yieldingly held in normal position by a different one of a series of four return springs 105, each spring being anchored to the framework 10 and its associated lever. Each of these four levers is provided with a return stop lug 106, each of which lugs is permanently adjustably bendable fore and aft of the machine relatively to the lever on which it is formed and is normally yieldingly held pressed forward against a stop device 107 which extends horizon-

tally transversely of the machine and is fixedly held to framework 10. Each "temporary shift" key lever 103 carries at its forward end a key 103a, and the "shift lock" key lever 104 carries a key 104a at its forward end. Each of the shift key levers is guided at its rear end in a different one of the slots 101 in the framework 10 and is also guided intermediate its rear end and its forward key-carrying end in a different one of a series of vertical guide slots 108 in a straight key lever guide comb 109 which extends horizontally transversely of the machine and is fixedly held to framework 10. The tappet-actuating lever 102—102a has an up-and-down extending arm 102a fulcrumed at its upper end on rod 100 and guided in one of the aforesaid slots 101 in framework 10, and said lever also has an arm 102 extending forwardly from arm 102a and guided intermediate its ends in one of the slots 108 in comb 109. Rocking of the tappet-actuating lever 102—102a from normal position is limited by engagement of a lug 102b on arm 102 of said lever with the closed lower end of the guide slot 108 provided for said lever in comb 109. Depression of either of the three shift key levers is limited by arrest of downward movement of arm 102 of lever 102—102a as will be apparent from the following description.

The tappet-actuating lever 102—102a is rockable to reciprocate fore-and-aft of the machine a bar-like tappet 110 which extends fore-and-aft of the machine. This tappet bar 110 has its forward end pivoted to the lower end of arm 102a of lever 102—102a by a horizontal pivot 111 which extends transversely of the machine. The lower portion of arm 102a is permanently adjustably bendable fore and aft of the machine. The tappet bar 110 is guided adjacent its rear end in a vertical guide slot 77a in the previously mentioned part 77 of framework 10, and is normally yieldingly held rocked about its pivot 111 against the closed upper end of said slot 77a by the previously mentioned return spring 78 for the clutch-controlling and dog-carrier-latching lever 12—13—14. Spring 78 is anchored at its upper end to arm 73 of said lever 12—13—14 and is anchored at its lower end to the rear end of the tappet bar 110.

The tappet 110 is formed at its upper side and adjacent its rear end with an upwardly extending and rearwardly facing shoulder 112 and with an upwardly extending and forwardly facing shoulder 113. The tappet, in all positions thereof, remains engaged in slot 77a, and, in all positions of the tappet, the shoulder 112 remains in rear of frame part 77 and the shoulder 113 remains forward of part 77. Shoulder 112 is normally disposed in front of a laterally bent lug 14a formed on the lower end of the pendent arm 14 of the clutch control and dog carrier arresting and latching lever 12—13—14. Shoulder 113 is normally disposed beneath a laterally bent lug 114a formed on the lower end of an upstanding tappet lever 114, which lever is fulcrumed intermediate its ends on the toggle anchor pivot 55 of toggle 51—53 and is formed at its upper end with a laterally bent lug 114b. Lug 114b is normally spaced forward from the hinge joint of said toggle 51—53 and is adapted to be disposed, when said toggle is in straightened locking condition, directly and closely in front of the pivotally connected ends of the toggle links in front of toggle hinge pivot 54. The lever 114 is rockable about pivot 55 fore and aft of the machine and is movable up and down substantially endwise by the

up-and-down movement of said toggle anchor pivot 55, which pivot is carried, as above described, by arm 40 of lever 38—40—41. The lower arm of the tappet lever 114 is guided in a fore-and-aft extending slot 115 in a part 116 of framework 10, and is normally yieldingly held against the closed rear end of said slot by a return spring 117 anchored to said arm and to an extension 39a of lever 38—39—40—41.

Upon rearward movement of tappet bar 110 by lever 102—102a, the lever 12—13—14 is rocked by shoulder 112 out of the path of travel of the dog-carrier 67 and clutch dog 69 to permit engagement of clutch elements 68 and 69 by the action of spring 71 on clutch dog 69. At the limit of rearward movement of tappet bar 110 determined by arrest of lever 102—102a by the means previously described, and the limit of ensuing downward endwise movement of tappet lever 114 by the clutch driven parts, the shoulder 113 on the tappet bar 110 is located behind and close to lug 114a on lever 114, and the tappet bar 110 is held rocked down about its pivot 111 by lever 114 against the pull of spring 78, with shoulder 112 out of the path of movement of lug 14a on control lever 12—13—14, as shown in Figure 3, thus permitting return of lever 12—13—14 to normal position by spring 78, independently of restoration of tappet 110 to its normal position, to enable lever 12—13—14 to disengage the clutch elements 68—69 at the end of a single revolution of the clutch. The tappet bar 110 is rocked down about pivot 111 by lever 114 during descent of said lever 114 and releases the clutch control lever 12—13—14 at an intermediate point in the revolution of the clutch as is apparent from Figures 2, 3 and 6.

It will be obvious that the bar 35, the lever 38—40—41, the segment rack 47—47a and tappet lever 114, when driven by the motor 62 into the position shown in Figure 3, cannot be restored by spring 43 to the position shown in Figure 2, until the then straightened toggle 51—53 is broken. It will also be obvious that, with the said power-actuable parts 35, 38—39—40—41, 47—47a and 114 fully shifted as in Figure 3, forward movement of tappet 110 by spring return of its actuating lever 102—102a by its return spring 105 will cause rocking of tappet lever 114 on its pivot 55 by shoulder 113, thus causing lug 114b on lever 114 to thrust rearward against the pivotally connected ends of the links of toggle 51—53 adjacent the toggle hinge pivot 54 to impart an initial collapsing movement to toggle 51—53 and thereby permit spring 43 to restore the said power-actuable parts to normal position and restore the segment 13 to its position conditioning the machine for lower case typing. Upon such return movement of actuating lever 102—102a (whenever brought about), the tappet lever 114 will be restored to normal position and the tappet 110 will resume its normal position.

It will also be obvious that the mutilated pinion 66 and the reciprocal segment rack 47 provides an automatic make-and-break operating connection between the driven element 69 of the single-revolution clutch 68—69 and the said motor-shiftable and spring-returned bar 35, lever 38—39—40—41, and tappet lever 114, which operating connection is established shortly following engagement of the clutch elements, is maintained during a predetermined portion of each revolution of the clutch sufficient to impart a predetermined shift to said parts, and is thereupon automatically broken before the completion of the

clutch revolution and remains broken until the clutch elements are again engaged for another revolution.

It will also be observed that, while said operating connection is broken, the motor-shifted segment rack 47, the lever 38-39-40-41, lever 114 and bar 35 are free to be returned by power spring 43 from their shifted position whenever released from locking action of toggle 51-53, so that no actuation of the clutch 68-69 is required to bring about restoration of said rack, levers and bar, but that a mere preliminary breaking of toggle 51-53 from fully straightened condition by rocking of tappet lever 114 by forward movement of tappet bar 110 is sufficient to permit spring 43 to effect such restoration with a concomitant restoration of the type bar segment 13 to its normal position.

It will also be noted that the throw impulsive to the segment rack by the mutilated pinion is great enough to permit full shifting of the type bar segment 13, and, preferably, is greater than that necessary for such full shifting, as above described. The provision of such excess throw prevents any possibility of the mechanism obstructing full gravitation of the segment into its position conditioning the machine for upper case typing.

The spring-retumed lever 102-102a for actuating tappet 110 is, in turn, operable by spring-retumed tappet means against the resistance of the return spring 105 for said lever. An oscillative and spring-retumed tappet device 118-119-120-121-122-123 is operable upon arm 102 of lever 102-102a to so rock said lever, said device being operable against the resistance of a return spring 124 by either of the "temporary shift" key levers 103 through a tappet action of either of said key levers on said device. The spring-retumed tappet-actuating lever 102-102a is also directly operable by a tappet action of "shift lock" key lever 104 thereon.

The said spring-retumed oscillative tappet device comprises a horizontal rock shaft 118 journaled in framework 10 and extending transversely of the machine adjacent the front ends of both of the key levers 103 and the front end of framework 10, two rearwardly extending rock arms 119 and 120 fixed on said shaft adjacent opposite sides of the machine, a horizontal pin 121 fixed to the rear end of the left hand arm 119 and extending transversely of the machine over the forward end of arm 102 of lever 102-102a and under the forward end of the left hand one of the key levers 103, a horizontal pin 122 fixed to the rear end of the right hand arm 120 and extending transversely of the machine under the forward end of the right hand one of the key levers 103, and a pendent rock arm 123 fixed on shaft 118. The return spring 124 for this oscillative tappet device serves also as a return spring for a pivoted latch 125 for the "shift lock" key lever 104, said spring being anchored at its opposite ends to arm 123 and latch 125. The pins 121 and 122 are normally urged upward against the under edges of their associated key levers 103 by spring 124. Depression of the key of either key lever 103 will rock the oscillative tappet device to thereby rock lever 102-102a and move tappet bar 110 rearward to trip the clutch control lever 72-73-74 to effect engagement of clutch elements 68 and 69, without movement of the other key lever 103 or of the key lever 104. Upon release of pressure on said depressed key, the bar 110 will resume normal position and, during its forward spring-

returned movement, will rock the lever 114 to initially collapse toggle 51-53, whereupon the segment will be restored by power of spring 43.

The "shift lock" key lever 104 is formed, intermediate its key 104a and the fulcrum of the key lever, with a laterally extending tappet lug 126 normally engaged over arm 102 of lever 102-102a for direct rocking of lever 102-102a by key lever 104 with a tappet action to actuate tappet 110 to trip clutch control lever 72-73-74 without movement of either of the shift key levers 103 and without movement of the oscillative tappet device 118-119-120-121-122-123.

The pivoted latch 125 for key lever 104 is pivoted at 130 on the framework 10, to rock about a horizontal axis extending transversely of the machine, and has an upstanding locking arm 127 formed at its upper end with a rearwardly projecting lug 127a, the rear edge of which lug is normally held yieldingly pressed rearward against the front edge of a laterally extending lug 128, which lug 128 is formed on key lever 104 between its key and fulcrum and is permanently adjustably bendable up and down. Latch 125 is also formed with a forwardly extending latch releasing arm 129 which extends under pin 121 on arm 119 of the oscillative tappet device and is normally spaced from said pin below the point to which the pin is depressible by the action of either key lever 103 on said device. Upon full depression of key 104a the latch is rocked by spring 124 to engage lug 127a over lug 128 on key lever 104 and latch said key lever down in its fully rocked position against return by its spring 105 when the typist releases key 104a. Depression and latching down of key lever 104 brings about a change of position of type bar segment 13 which conditions the machine for upper case typing and also prevents restoration of said segment to normal position until latch 125 is released. Release of latch 125 and resultant restoration of the segment 13 to normal position may be thereafter effected by depression and release of either of the shift keys 103a. In the latched position of key lever 104 (shown in Figure 4) it will be observed that releasing arm 129 of latch 125 has been carried up (by rocking of the latch into latching position) into the field of downward movement of pin 121 of the oscillative tappet device, so that rocking of the latter device by depression of either of the keys 103a will cause said pin 121 to depress latch release arm 129 and thereby rock the latch 125 to release the key lever 104 which will immediately rise to normal position under the influence of its return spring 105. As soon as the key 103a, depressed to release the latch, is itself released, this key and its lever 103 will rise to normal position and the latch 125 and the oscillative tappet device will be restored to normal position by spring 124. Restoration of key 104a and its lever 104 to normal position likewise permits restoration of lever 102-102a and tappet 110 to normal position, with resultant restoration of the type bar segment 13 to normal position in the manner hereinbefore explained.

To reduce the power required to lift the segment 13 and to thus avoid the necessity of using a very strong spring 43, reduce the motor power required to advance the link 35, and reduce shock and noise and wear in operation of the case shift mechanism, a counterbalance spring 133 is preferably provided for counterbalancing the major portion of the weight of the segment 13 and of the parts mounted thereon. This spring 133 is anchored at its forward end to a stud on plate 24

and is anchored at its rear end to the forward end of a bolt 134. Bolt 134 is slideable endwise through a guide aperture in a part of framework 10, and a nut 135 is threaded on the rear end of the bolt and abuts the rear face of this frame part. By screwing nut 135 along the bolt, the normal tension of the counterbalancing spring 133 may be varied.

To prevent possible mal-operation of the case shift mechanism by a staccato blow on either of the temporary shift keys or depression and instant release of either of said keys while the machine is conditioned for lower case typing, a safety latch 136 is preferably provided. This latch is pivoted adjacent its forward end on link or bar 110 at 137 to swing up and down at one face of said link or bar. Adjacent its free rear end, this latch is formed with an upstanding lug 138 normally held yieldingly urged upward against the closed upper end of guide slot 77a by a light spring 140 which is connected to said latch and to bar 110. Adjacent its free rear end, said latch is formed with a pendent stop lug 139 which is bent laterally at its lower end to underlie the lower edge of bar 110 at a point spaced slightly below said edge in the normal position of bar 110 and latch 136. Upon rearward movement of bar 110 far enough to trip the single-revolution clutch device, the latch rocks upward to engage lug 139 against the under side of bar 110 and engage lug 138 against the rear face of the slotted part 77 to latch bar 110 and lever 102-102a in actuated position until lever 114 descends and rocks bar 110 downward, whereupon the latch 136 will be carried bodily downward with the bar to release the latch as shown in Figures 3 and 6. If the depressed temporary shift key has already been released, parts 110 and 102-102a will now assume normal position and actuate the toggle-unlocking lever 114 to bring about restoration of the segment to normal lower case position. In the absence of the latch 136, it might be possible, upon an unusually rapid and abnormal operation of either of the temporary shift keys, for the key to return before descent of lever 114, which would result in the segment moving to and remaining in the position thereof which conditions the machine for upper case typing. The latch 136 and bar 110 extend through the guide slot 77a in all positions of said latch and said bar.

We claim:

1. In a typewriting machine having an operation-effecting element reciprocal from and to a normal stationary position thereof to perform its work, the combination with said element of a rack reciprocal from and to a normal stationary position thereof, a mutilated pinion rotative from a normal stationary position thereof to drive said rack in one direction of the reciprocating movement of the rack and thereupon disengage from the rack during each revolution of the pinion, and key-controlled power-actuated means for rotating said pinion through a single revolution only upon each actuation of said means, said rack being normally disengaged from said pinion, and said element and rack being constantly connected for concomitant reciprocation thereof from and to normal position and being constantly biased to return to normal position.

2. In a typewriting machine having an operation-effecting element reciprocal from and to a normal stationary position thereof to perform its work and normally biased to move to said stationary position, the combination with said element of a depressible control key, a single-rev-

olution clutch having normally disconnected driving and driven elements, means for constantly rotating the driving element of the clutch while the machine is in use, a normally broken operating connection between said reciprocal element and the driven element of the clutch automatically temporarily connectible once during each revolution of the driven clutch element to move said reciprocal element from its normal position, means operable upon depression of said control key to effect engagement of the driving and driven elements of the clutch for a single revolution only, latching means automatically operable to latch said reciprocal element in its shifted position, and means controlled by return movement of said key to operate upon said latching means to free said element for automatic restoration of the latter to the normal position into which it is biased to move.

3. In a typewriting machine having an operation-effecting element oppositely movable from and back to a normal stationary position, the combination with said element of spring means connected with said element to constantly yieldingly urge the element into its normal stationary position, a single revolution clutch having normally disconnected rotative driving and driven clutch elements, an electric motor for constantly rotating the driving element of said clutch in one direction while the machine is in use, means for at will temporarily connecting the clutch elements for a single revolution only of the driven clutch element from a normal stationary position of the latter, and means operable on each such revolution of the driven clutch element to shift said operation-effecting element from the normal stationary position of the latter and against the force of said spring means and to thereafter leave said operation-effecting element disconnected from the driven clutch element.

4. In a typewriting machine having an operation-effecting element oppositely movable from and back to a normal stationary position, the combination with said element of spring means connected with said element to constantly yieldingly urge the element into its normal stationary position, a single revolution clutch having normally disconnected rotative driving and driven clutch elements, an electric motor for constantly rotating the driving element of said clutch in one direction while the machine is in use, means for at will temporarily connecting the clutch elements for a single revolution only of the driven clutch element from a normal stationary position of the latter, and means operable on each such revolution of the driven clutch element to shift said operation-effecting element from the normal stationary position of the latter and against the force of said spring means and to thereafter leave said operation-effecting element disconnected from the driven clutch element.

5. In a typewriting machine having a support which is shiftable alternately to two positions, one of which is higher than the other, to condition the machine for typing characters of two different printing cases, the combination with said support of an intermittently operable mechanism having a one-way power transmitting connection with the support for impelling the support from its lower to its higher position, spring

means for actuating said mechanism to impel the support from its lower to its higher position, a locking device which is automatically operable to lock the support in said higher position and which is adapted to be tripped by said mechanism to free the support, a source of power for actuating said mechanism to concomitantly free the support from locking action thereon of said locking device and from upward impelling action thereon of said mechanism to thereby permit gravitation of the support from its higher to its lower position, and case selecting means for initiating actuations of said mechanism by said spring means and by said source of power in alternation and for controlling the time interval between the alternating actuations of said mechanism.

6. A typewriting machine for typing lower and upper case characters having, in combination, a reciprocal rack, means for determining one limit of reciprocating motion of the rack, a spring connected with the rack for driving the rack to said limit, a single-cycle power means for driving the rack in opposition to said spring to a second limit of reciprocating motion of the rack and including a mutilated pinion which is normally stationary and normally disengaged from the rack and which is coactive with the rack during each revolution of said pinion to engage the rack and drive it from said first to said second limit and is rotative through 360 degrees only by each cycle of operation of said power means, means for automatically holding the rack at said second limit of motion thereof when said rack is driven to said limit by said power means, case-changing means shiftable alternately to two case-changing positions in response to alternate movements of the rack to said two limits for conditioning the machine in alternation for typing lower and upper case characters, and case-selecting means operable alternately to initiate a cycle of operation of said power means and to free the rack from holding action of said holding means.

7. A typewriting machine as claimed in claim 6, wherein the single-cycle power means comprises a rotary electric motor which operates constantly while the machine is in use, and a single-revolution clutch device having a driving member constantly rotated by said motor and a driven member connected positively with said pinion to rotate the latter and normally disconnected from the driving member, said clutch members being constantly biased to engage, and wherein the case selecting means is alternately operable respectively to trip the clutch device for a single operation thereof and to free the rack from holding action of said holding means without tripping the clutch device.

8. A typewriting machine having, in combination, a type carrier support shiftable alternately to two positions, one higher than the other, to condition the machine for typing characters of different printing case, a reciprocal rack having a one-way motion transmitting connection with said support for lifting the support from the lower to the higher of said positions, means for arresting movement of the rack in support-lifting direction at one limit of reciprocating motion of the rack, a spring connected with the rack for driving the rack in one direction to said limit to lift the support to said higher position, a single-cycle power means for driving the rack in opposition to said spring to a second limit of reciprocation of the rack which permits gravitation of

the support into the lower one of said two positions thereof, said power means including a mutilated pinion which is normally stationary and normally disengaged from the rack and which is coactive with the rack, during each revolution of said pinion, to drive the rack to said second limit and is rotative through only 360 degrees by each cycle of operation of said power means, locking means for automatically locking the rack against driving thereof by said spring upon driving of the rack by said means to said second limit of reciprocation of the rack, and case selecting means operable in alternation to initiate a cycle of operation of said power means and to release the rack from locking restraint of said locking means.

9. A typewriting machine for typing characters of two printing cases having, in combination, a reciprocal rack biased to move in one direction of its reciprocating movement to a predetermined limit, a rotary electric motor which runs constantly while the machine is in use, a normally stationary mutilated pinion, a single-revolution clutch device for coupling said pinion with said motor for rotating the pinion 360 degrees only and thereupon automatically uncoupling said pinion from the motor and arresting it in its normal stationary position, the teeth of said pinion being normally out of the path of reciprocating movement of the rack and being engageable with the teeth of the rack during each revolution of the pinion to drive the rack a predetermined extent in the other direction of its reciprocating movement, case-changing means responsive to each stroke of the reciprocable rack, locking means for automatically detaining the rack in the position into which it is drivable by said pinion, and case-selecting means operable alternately to respectively put said clutch device into action and to release the rack from detention by said locking means.

10. In a typewriting machine having a main framework and a type support which is shiftable relatively to said framework to two limits, one higher than the other, for conditioning the machine respectively for typing lower case characters while said support is maintained at the higher one of said limits and for typing upper case characters while said support is maintained at the lower one of said limits, the combination with said framework and support of a reciprocal element having a predetermined throw, a spring connected with said element for driving the element to one predetermined limit of its reciprocating movement, power means transitorily operable on said element to drive said element in opposition to said spring to an opposite limit of its reciprocating movement, a toggle having an anchor fixed to the framework and a movable anchor positively connected with said element for locking said element at its said opposite limit of movement against reverse driving by said spring, a second toggle having an anchor fixed to the framework and a movable anchor positively connected with said support for locking the support at its higher limit of shift against downward movement to its lower limit of shift, said element having a cam portion transitorily operable on said second toggle to initiate collapsing of the latter upon initial movement of said element by said power means and having a one-way driving connection with the movable anchor of said second toggle for driving said anchor to lift the support from its lower to its higher limit upon driving of said element by said spring, a depressi-

ble case shift key, means controlled by depression of said key for causing said power means to drive said element, and means controlled by return of said key to transitorily operate on the first-mentioned toggle to initiate collapsing of the latter for releasing said reciprocal element for driving by said spring.

11. A typewriting machine having a main framework, a rotary electric motor which is constantly energized while the machine is in use, a type support shiftable up and down to two limits for case changing, a toggle connected with said framework and support for straightening of the toggle for locking the support at the higher one of said two limits, a reciprocal element operable on said toggle for lifting the support from the lower to the higher of said limits and for freeing said support for gravitation of the latter from the higher to the lower of said limits on alternate strokes of said element, a spring connected with said element for imparting support-lifting strokes to the element, means for transitorily connecting said motor with said element for imparting support-freeing strokes to said element by power of said motor, a second toggle connected with said framework and said element for straightening of the toggle to lock said element at the end of each support-freeing against movement in support-lifting direction, means operable on said second toggle to free said element for driving by said spring, and case-selecting means for rendering the two last-mentioned means alternately effective.

12. In a typewriting machine having a reciprocal operation-effecting element, key-controlled power-actuated means to reciprocate said element comprising, in combination, a toothed segment oscillative about a fixed axis and connected with said operation-effecting element to produce reciprocal movement of the element through oscillative movement of the segment, a spring constantly connected with said segment to drive the segment in one direction about its axis to a normal stationary position of the segment, a mutilated pinion rotative in one direction about a fixed axis parallel to that of the segment to, during each revolution of said pinion, first engage and drive said segment in opposition to said spring and thereupon disengage from the segment, means to normally lock said pinion against rotation at a single rotated position of the pinion in which said pinion is demeshed from the segment, a rotary shaft which is constantly power rotated while the machine is in use, a control key biased to a normal position, and means responsive to movement of said control key from its normal position to effect unlocking of said pinion and connect it with said shaft to drive the segment in opposition to the spring and responsive to pinion driven movement of the segment to disconnect the pinion from the shaft and effect relocking of the pinion at the end of a single revolution of the pinion from its normally locked position.

13. In a typewriting machine having work-effecting means reciprocal from and to a normal stationary position, the combination with said work-effecting means of a control key therefor movable from a normal position to which it is biased to, return, a shaft which is constantly power rotated while the machine is in use, a mutilated pinion rotative about a fixed axis, a single-revolution clutch, responsive to movement of said key from normal position, to rotatively drive said pinion from said shaft through a single revolution and lock said pinion in a normal stationary position until said key is again moved from normal position, and a reciprocal rack in response to the strokes of which said work-effecting means reciprocates and with which said pinion transitorily meshes during each revolution of the pinion to drive said rack from a normal stationary position to which said rack is biased to return.

14. In a typewriting machine having an operation-effecting element reciprocal from and to a normal stationary position thereof in performing its work, the combination of a rack reciprocal from and to a normal stationary position to which it is biased to return, a mutilated pinion from which the rack is normally disengaged and which is rotative from a normal stationary position of the pinion to first engage the rack and drive it in opposition to its bias from its normal position and thereupon disengage from the rack during each revolution of said pinion, a single-revolution clutch including driving and driven clutch members and a stop to disengage said members and arrest rotation of the driven member, power means for constantly rotating the driving clutch member while the machine is in use, means for driving said pinion from the driven clutch member when the latter is rotated, key-controlled means having a control key biased to a normal position, and controlled by movement of said key from normal position to both withdraw said stop from its arresting and clutch disengaging position and to engage the clutch members, means actuated by rotation of the driven clutch member to restore said stop to its arresting and clutch disengaging position prior to completion of a single revolution of said driven clutch member and independently of restoration of said control key to its normal position, and means connecting said rack to said operation-effecting element to produce reciprocation of said element.

15. The combination as claimed in claim 14, including means for blocking biased return of the rack following each disengagement of the mutilated pinion from the rack, and means controlled by return of said control key to its normal position for releasing said blocking means and permitting biased return of said rack.

CHARLES WALKER.
WILLARD H. WADE.
